(57) **CLAIM**

I claim the ornamental design for the re-usable rigid dinner plate, as shown and described.

DESCRIPTION

FIG. 1 is a perspective of the re-usable rigid dinner plate of my new design;

FIG. 2 is a top plan view thereof;

FIG. 3 is a bottom plan view thereof; and,

FIG. 4 is a front view thereof, with rear, left-side, and right-side views being identical.

1 Claim, 2 Drawing Sheets
